UNITED STATES PATENT OFFICE.

MARVIN BLAIR AND CHARLES O. GROVE, OF ELECTRA, TEXAS.

SWIVEL SOCKET.

Application filed April 22, 1926. Serial No. 103,837.

This invention relates to well tools and equipment and it refers more particularly to swivel rope sockets for cable drilling, the principal object being to provide a wire line socket in which certain expedients are provided whereby to render possible a more speedy and efficient coupling and likewise to avoid the necessity of threading the cable through the tool before applying the end swivel socket.

The invention further aims to provide a rope socket which may be readily cleaned of accumulations of sand and mud, as well as to provide for the insertion and removal of the cable without requiring that the swivel socket be removed and replaced at each operation.

With these and other objects and advantages in view, the invention resides further in the salient features of construction and assembly of parts which will be manifested in the course of the following detail description and illustrated in the accompanying drawings, wherein:

Figure 1 represents an elevational view of the improved swivel rope socket.

Figure 2 is a view in vertical cross-section.

Figure 3 represents a perspective view of the locking bar.

Figure 4 is an elevational view of the socket, showing the cable end before insertion, and the locking bar partially inserted, and

Figure 5 is a cross-section on lines 5—5 of Figure 4.

It is of course a well known precedent to employ, in cable drilling a connection of similar construction to that shown, but in previous structures, it was required to insert the end of the cable into the top of the socket, draw it through the aperture in the side, and apply the plug or rope ends. The present invention proposes to slot the side of the body in such a manner as to permit the plug to be first applied, then inserted into the socket and clamped.

In continuing more in detail, reference is directed to Figure 1, showing the body 1 in vertical elevation which has the usual opening 2 therein. A slot 3 begins at this opening and extends out at the top of the body, and is provided with shoulders 4 intermediate its ends, the purpose of which will be later made clear. This slot likewise has on either side, grooves 5, as particularly apparent in Figure 4.

Now, referring to Figure 2, a shoulder 6 is shown formed interiorly of the body 1, in the cylindrical cavity 7, for the purpose of retaining the plug or rope end socket 8, on the end of the rope 9. The body 1 is further provided with the usual wrench engaging square 10, and threaded tool receiving box 11.

After the rope end 8 is securely affixed to the end of the rope 9, it is placed into the opening 2, allowing the rope to enter the slot 3, to assume the position shown in Figure 2. After this done, the locking bar 12, exclusively shown in Figure 3, is inserted into the slot 3, whereupon it slides downwardly and its lower end completely covers the opening 2. It will be observed in Figures 2 and 4, as well as 5, that flanges 13 are provided on each side of the bar 12, which are adapted to ride in the grooves 5 of the slots, previously mentioned. Upon reaching the lowest point in the slot 3, the bar 12 is then in a position to permit the latch springs 14 on the bar, as in Figures 3 and 4, to spring outwardly and engage behind the shoulders 4 in the slot 3, to positively hold the bar against upward movement.

It is particularly pointed out that no strain whatever is imposed upon the bar 12, all of such strain being entirely restricted to the shoulder 6, as in Figure 2, the bar 12, acting only in the capacity of a retaining element to prevent displacement of the cable, during operation of the tool within the well. An auxiliary locking means in the form of a set screw 15 may be employed to aid in holding the bar in proper position within the slot 3, but which is not essentially necessary. In order to remove the cable 9 for the purpose of repairing or cleaning the tool, it is required only to compress the springs 14 and pry the bar 12 from its position within the slot and release the plug 8 from the opening 2.

While the invention has been specifically referred to in detail as to structure and purpose, it should be understood that it is not desired that the invention be restricted to such limitation, and that certain modifications may be resorted to as practicable, provided such modifications remain within the scope of the appended claims.

We claim:

1. A swivel rope socket including a body having a longitudinal bore and an aperture

exteriorly entering said bore provided with a slot extending to the top of said body; shoulders in said bore adjacent the said aperture; means to permit of the insertion of a cable and cable end socket into said aperture and slot; and a locking bar having latch springs thereon insertable in said slot whereby said springs will engage shoulders in the side of said slot to hold said bar 10 against upward movement in said slot.

2. A swivel rope socket including a body having a longitudinal bore and a slot partially extending along the said body opening into said bore and terminating into an enlarged opening; means to permit the insertion of a cable and cable socket into said bore; a shoulder in said bore for holding said cable socket from upward movement; and a locking means comprising a bar slideable in said 15 slot having spring means normally engageable in shoulders in opposing sides of said slot when in locked position.

3. A swivel rope socket including a hollow body having an opening therein and a slot 20 extending from said opening to the top of said body provided with recesses in its sides; means for holding a cable end socket in the hollow portion of said body, and a locking bar slideable in said slot having 25 springs on its sides arranged to engage within said recesses when in normal locked position.

4. A swivel rope socket including a hol-

low body having an opening therein and a slot extending from said opening to the top 35 of said body provided with opposed recesses; an annular shoulder in the hollow of said body to receive a cable end socket; a bar slideable in said slot, and springs on opposing sides of said bar arranged to be received in the recesses of said slot.

5. A swivel rope socket including with a hollow body having a recessed slot and opening thereon a means for locking a cable in the hollow of said body; said means comprising a bar slideable lengthwise in said slot to cover said opening and springs on opposing sides of said bar disposed so as to be received in the recesses of said slot.

6. A device of the character described 50 comprising a hollow body having a recessed slot and opening in its side communicating with said hollow portion; means to permit of the insertion of a cable and cable socket in said hollow portion; and means for retaining said cable and socket against movement from said hollow portion; said means comprising a bar slideable lengthwise in said slot having springs on its sides disposed to be received in the recesses of said slot when 55 in locked position.

In testimony whereof we affix our signatures.

MARVIN BLAIR.
CHARLES O. GROVE.
